ELECTRIC SWITCH MECHANISM

Arthur Palme, Pittsfield, Mass., assignor to General Electric Company, a corporation of New York

Application March 31, 1934, Serial No. 718,391

1 Claim. (Cl. 200—146)

My invention relates to electric switch mechanisms and is particularly applicable in connection with switches for changing transformer tap connections. It is often desirable to maintain constant voltage on the secondary circuit of a transformer but changes in the load supplied by the transformer tend to cause this voltage to vary. Transformers are consequently commonly provided with winding taps and means for changing 10 tap connections to vary the voltage ratio and thus maintain the desired voltage in the secondary circuit under varying load conditions. It is further desirable in many cases that the tap connections be changed without interrupting the load current supplied by the transformer. The general object of the invention is to provide an improved electric switch mechanism particularly adapted for these purposes.

The invention will be more fully explained in 20 the following description taken in connection with the accompanying drawings in which Fig. 1 is a side view, partly in section, of a switch mechanism constructed in accordance with the invention and applied in connection with a transformer; Fig. 2 is a front view of the switch mechanism; and Figs. 3 and 4 are explanatory circuit diagrams.

Like reference characters indicate similar parts in the different figures of the drawings. 30 The transformer 10 shown in Fig. 1 of the drawings is immersed in an insulating liquid 11 in a casing 12. A switch casing 13 is secured over an opening in the side of the transformer casing 11', the back of the switch casing forming 35 a partition 14 which is preferably liquid tight between the transformer and switch compartments provided by the two casings.

A switch 14' shown in Figs. 1 and 2 is immersed in an insulating liquid 15 in the switch casing 13. The switch 14' includes two fixed contacts 16 and 17 on the ends of two conductive rods 18 and 19 respectively which extend through bushings 20 in the partition 14 into the transformer casing 11' where they are connected to spaced winding taps of the transformer 10. The switch 14' also includes two movable contacts 21 and 22 carried by contact arms 23 and 24 respectively. The contact arm 24 projects from a conductive sleeve 25 rotatable on a conductive rod 26 which extends through a bushing 20 in the partition 14 into the transformer casing 11' where it is connected through a bushing 27 to an outside terminal 28. The contact arm 23 projects from a conductive sleeve 29 surrounding the sleeve 25 but insulated from it by an insulating bushing

30. An impedance 31, wound on an insulating spool 32, is mounted on the sleeve 29 and connected between the movable contacts 21 and 22 through their contact arms 23 and 24 and sleeves 29 and 25. The impedance 31 may be inductive 5 or not as desired. To avoid resistance between the contact arm 24 and the conductive rod 26, they are preferably connected by a flexible connection 32'. Each of the fixed contacts 16 and 17 is shown as including two contact blades 33 10 which have contact surfaces projecting into the paths of the movable contacts 21 and 22 respectively. The sleeves 25 and 29 and the impedance 31 are rigidly connected together so that there can be no relative movement between them and 15 consequent injury to the electrical connections between the impedance and sleeves. The electrical circuits of the arrangement which has been described are shown diagrammatically in Fig. 3 where the fixed contacts 16 and 17 are connected 20 to taps at one end of the tappet transformer winding. If desired, the tappet winding may be formed in two sections as shown diagrammatically in Fig. 4, the fixed contacts 16 and 17 being connected to taps in one section of the winding and 25 the other section of the winding being connected between the movable contacts 21 and 22 and the outside terminal of the transformer.

Both of the movable contacts 21 and 22 are normally in contact with one or the other of 30 the fixed contacts 16 and 17 depending on the desired voltage ratio of the transformer 10, both movable contacts being shown on the fixed contact 16 in Fig. 1. The movable contacts are operated by two electromagnets 34 and 35 with 35 their plungers 36 and 37 connected by insulating rods or tubes 38 and 39 to spaced ears 40 and 41 projecting from opposite sides of the sleeve 25. The electromagnets 34 and 35 may be energized and controlled in any manner and from 40 a remote point if desired. If the electromagnet 35 is energized, it will pull the ear 41 up and rotate the sleeves 25 and 29 to move the movable contacts 21 and 22 from the fixed contact 16 to the fixed contact 17. If the other electro- 45 magnet 34 is energized, it will similarly pull the ear 40 up to move the movable contacts 21 and 22 from the fixed contact 17 to the fixed contact 16.

The switch with its impedance 31 is arranged 50 to be operated without interrupting the current flowing through its contacts. In the arrangement shown, the impedance 31 is connected between the two movable contacts 21 and 22. The two contact blades 33 of each fixed contact are 55

arranged side by side but the two movable contacts 21 and 22 are angularly displaced about their common axis. Thus, one of the movable contacts will leave a fixed contact ahead of the other movable contact and will then reach the other fixed contact first. The fixed contacts 16 and 17 are so spaced that the angularly displaced movable contacts may bridge them for a brief instant while they are moving from one fixed contact to the other. Assume that the movable contacts 21 and 22 are both on the fixed contact 16 as shown most clearly in Fig. 1 and they are to be moved to the fixed contact 17. In this initial position of the contacts, practically all the current will flow through the movable contact 22 because the impedance 31 is in series with the other movable contact 21. The movable contact 22 first leaves the fixed contact 16 breaking the circuit through this movable contact and all the current then flows through the movable contact 21 and the impedance 31. The movable contact then reaches the fixed contact 17 and current flows through both movable contacts. The impedance 31 is now connected between the two winding taps of the transformer 10 and the voltage between the two taps causes a circulating current in the impedance which should be of such value as to limit this current to a safe value. The movable contact 21 then leaves the fixed contact 16 and all the current flows through the other movable contact 22. The movable contact 21 finally reaches the fixed contact 17

but little current will flow through it because of the impedance 31 in series with it. The movable contacts 21 and 22 may be moved back to the fixed contact 16 in similar manner but the steps will of course be reversed.

5

The contact arms 23 and 24 with their movable contacts 21 and 22 and the impedance 31 are all rigidly connected together so that there is never any relative motion between these parts. Consequently, no flexibility is necessary in the 10 connections between the impedance and the contacts and these connections may be short and direct and not liable to injury from the movements of the switch parts.

The invention has been explained by describ- 15 ing and illustrating a particular form of switch and one application thereof but it will be apparent that changes may be made without departing from the spirit of the invention and the scope of the appended claim.

20

What I claim as new and desire to secure by Letters Patent of the United States is,

A switch including two fixed contacts, a rotatable contact support, two movable contacts rigidly secured to said support and angularly dis- 25 placed about its axis, an insulating spool surrounding said support, an impedance wound on said spool and electrically connected between said movable contacts, and means for rotating said support to move said movable contacts alter- 30 nately from one fixed contact to the other.

ARTHUR PALME.
